UNITED STATES PATENT OFFICE.

FRANK L. COES, OF WORCESTER, MASSACHUSETTS, ASSIGNOR TO LORING COES & COMPANY, INCORPORATED, OF WORCESTER, MASSACHUSETTS, A CORPORATION OF MASSACHUSETTS.

WRENCH-HANDLE.

SPECIFICATION forming part of Letters Patent No. 691,046, dated January 14, 1902.

Application filed November 9, 1901. Serial No. 81,850. (No model.)

To all whom it may concern:

Be it known that I, FRANK L. COES, a citizen of the United States, residing at Worcester, in the county of Worcester and State of Massachusetts, have invented a new and useful Improvement in Wrench-Handles, of which the following, together with the accompanying drawings, is a specification sufficiently full, clear, and exact to enable persons skilled in the art to which this invention appertains to make and use the same.

My present invention relates to an improved construction in wrench-handles by which the handle-frame is provided with strap-arms or band-sections formed integral thereon and projecting from its outer corners at or near the portion of greatest diameter and adapted to be closed or folded about the wood handle-plates and their ends secured by rivet-pins or suitable locking attachment, as more fully hereinafter explained.

The object of this invention is to render the handle efficient, strong, and durable, to afford an increased metal wearing-surface outside the wood, and to securely confine the wood parts upon the frame and also prevent checking or splitting.

The particular subject-matter claimed is hereinafter definitely specified and the features of improvement illustrated in the accompanying drawings, wherein—

Figure 1 represents a side view of a wrench having a handle embodying my invention. Fig. 2 is an edge or back view of the handle-frame and one of the wood side plates. Fig. 3 represents on a somewhat larger scale a transverse section of the handle at line $x x$ on Fig. 1. Fig. 4 is a transverse section of the handle-frame, showing the integral band-sections in extended position or as primarily formed in casting. Figs. 5 and 6 represent transverse sections at similar positions illustrating modification in the form and manner of securing the ends of the band-sections.

Referring to the drawings, A indicates the wrench-bar carrying the fixed jaw and having a shank portion that extends into or through the handle. B indicates the movable jaw sliding on the bar, and C the adjusting-

screw, all disposed in well-known or suitable arrangement.

D indicates the metal handle-frame, which comprises a collar portion 2, longitudinally-extending edge bars 3 for filling out the handle-form and giving support upon the front and rear edges of the bar-shank A', as heretofore practiced, and said edge bars integrally united by transverse stays or a connecting web or webs 4, bridging across the intervening bar-shank space. The collar portion, edge bars, and bridging-web are preferably all integral in the frame-casting.

In my present invention I provide upon the outer angles or side edges of the handle-frame D, approximately at its position of greatest width, oppositely-arranged projecting arms, straps, or band-sections $m m'$, which are cast or formed integral with the edge bars 3, said band-sections being primarily disposed in standing relation, (see Figs. 2 and 4,) but are adapted to be subsequently closed or folded inward about the side plates or wood-scales E at their mid-length, which latter have a suitable groove formed on their exterior at 6 for receiving the band-sections when the parts are assembled in the completed wrench.

The straps or band-sections are preferably formed as four projections of such length that their ends will abut or match onto each other when folded or clasped about the side plates, thereby forming a full circumferential band or ring of metal around the handle and integral with the edge bars, as illustrated.

When the parts are assembled, the wood scales E are seated upon the sides of the frame D, the end tenon under the collar-rim 8. The band-sections are then bent or folded inward by means of suitable tools, sinking the band into the groove of the plates E and bringing their abutting ends together at 5, (see Figs. 1 and 4,) making a complete circlet-clasp. The ends of the band-sections are then drilled and the rivet-pins 9 passed through the handle-plates, bar-shank, and ends of the band-sections at the opposite sides of the handle, the ends of said pins being riveted flush with the exterior, thereby rigidly connecting the

parts and securing the end of the band-sections. The exterior of the band portions, side plates, collar, and tip-piece are finished off with a smooth flush surface. The band 5 affords a metal wearing-surface surrounding the swell of the handle and protects the wood or non-metallic plates from rapid wear.

In lieu of placing the two rivets 9 in transverse alinement the ends of the band-sections 10 $m\ m'$ can be disposed in adjacent offsetting positions and the rivets 9 disposed in longitudinal alinement in respect to their holes through the bar-shank.

In some instances the meeting ends of the 15 band-sections $m\ m'$ may be made so as to lap onto each other, as at 10 or at 11, and the overlapping ends secured by a single rivet-pin 19. Such modification is illustrated in Fig. 5.

20 Another modification is illustrated in Fig. 6, wherein two band-sections $n\ n'$ are formed integral upon opposite sides of the handle-frame D, each band-section being of sufficient length to fold or clasp around one of the side 25 plates E and its end adapted to be secured to the opposite edge of the handle-frame at 13 by an interlock joint, screw, or rivet fastening.

What I claim as of my invention, and desire to secure by Letters Patent, is—

30 1. In a wrench-handle, a circumferential band composed of band-sections formed integral with the handle-frame and folded around the side plates or handle-scales, and having their ends secured by rivets or interlock fastenings.

35 2. In a wrench-handle, the metal handle-frame provided at its outer edges with arms, straps or band-sections integrally cast or

formed upon the sides thereof, said straps curved or bent inward to circumferentially 40 embrace the side plates, the straps from opposite edges having their unattached ends disposed adjacent to each other, in combination, with the wooden side plates having circumferential grooves for the reception of said 45 straps, and securing pins or rivets that confine said adjacent ends within the grooves and connect the sides of the handle.

3. In a wrench-handle, the handle-frame provided with projecting straps or band-sections integrally cast or formed upon the sides of said handle-frames, said band-sections circumferentially embracing the wood side plates or handle-scales, their opposite ends abutting upon each other at the sides of the handle 55 and respectively secured by rivets that extend through the handle and bar-shank and connect the band ends at the opposite sides of the handle, substantially as set forth.

4. In a wrench-handle, the handle-frame 60 comprising a collar portion, longitudinally-extended edge bars, and a transverse web, or webs, uniting said edge bars across the shank-receiving space, and provided with projecting band-sections adapted for surrounding the 65 non-metallic side plates, said collar, edge bars, webs and band-sections all formed integral in a single piece, and adapted to receive the bar-shank and to support the side plates, in the manner set forth.

Witness my hand this 7th day of November, 1901.

FRANK L. COES.
